CLAIM

The ornamental design for an “on-vehicle charger and wireless earphone assembly” as shown and described.

DESCRIPTION

FIG. 1 is a rear, top and left side perspective view of an on-vehicle charger and wireless earphone assembly, with the earphone being removed for ease of illustration showing my new design;

FIG. 2 is a front elevational view thereof;

FIG. 3 is a rear elevational view thereof;

FIG. 4 is a left side elevational view thereof, a right side elevational view thereof being symmetrical to the left side elevational view thereof;

FIG. 5 is a top plan view thereof;

FIG. 6 is a bottom plan view thereof;

FIG. 7 is a rear, top and left side perspective view thereof with the charger portion being removed for ease of illustration;

FIG. 8 is a front elevational view thereof, a rear side elevational view thereof being symmetrical to the front elevational view thereof;

FIG. 9 is a left side elevational view thereof, a right side elevational view thereof being symmetrical to the left side elevational view thereof;

FIG. 10 is a top plan view thereof;

FIG. 11 is a bottom plan view thereof;

FIG. 12 is a rear, top and left side perspective view of an on-vehicle charger and wireless earphone assembly showing my new design;

FIG. 13 is a front elevational view thereof;

FIG. 14 is a rear elevational view thereof;

FIG. 15 is a left elevational view thereof, a right side elevational view thereof being symmetrical to the left elevational view thereof;

FIG. 16 is a top plan view thereof; and,

(Continued)

FIG. 17 is a bottom plan view thereof.

The broken lines shown represent portions of the on-vehicle charger and wireless earphone assembly which form no part of the claimed design.
